UNITED STATES PATENT OFFICE.

JAMES H. MUNRO, OF NEWARK, NEW JERSEY, ASSIGNOR OF ONE-HALF TO JOHN MILTON VAN ORDEN, OF NEWARK, NEW JERSEY.

CUTTING APPARATUS.

1,134,217.

Specification of Letters Patent.

Patented Apr. 6, 1915.

Application filed January 2, 1909. Serial No. 470,386.

To all whom it may concern:

Be it known that I, JAMES H. MUNRO, of Newark, New Jersey, have invented certain Improvements in Cutting Apparatus, of 5 which the following description, in connection with the accompanying drawings, is a specification, like letters on the drawings designating like parts.

This invention relates to cutting apparatus, and is of special utility when embodied in apparatus for trimming to the desired size and shape the sheets or units of roofing material known as "inlaid slate" which usually are formed by cementing with 15 an elastic cement such as asphalt a number of small squares of slate (slightly thicker than the slates used commercially on roofs) upon a backing of flexible material such as roofing paper, this composite material not 20 being capable of treatment by the usual devices employed by slate-roofers, on account of the tough paper, the brittle character of the slates, and the tenacious quality of the cement. It will be understood however that 25 I contemplate the use of my improvements in any field for which they are adapted by their nature.

An important object of my invention is to provide for a rapidly working device which 30 can be placed in the hands of relatively unskilled workmen whether used on a roof to trim the individual units to fit in places requiring unusual shapes, or whether to be used in the mill where the slates are manufactured, to trim the units to standard size, 35 it being requisite in each instance that the cut edges of the slate, backing and binding layer of cement shall be sharply defined and clean as well as true, so as to make possible 40 an exact fit when the units are laid with their cut edges in abutting relation.

Another important object of my invention is to provide apparatus in which a plurality of such cutting members shall be arranged 45 to coöperate for the trimming at a single stroke of the margins of one or more of these slate units.

The various features of my invention will be illustrated and described fully in the accompanying drawings and specification and pointed out in the claims.

In the drawings:—Figure 1 is a view in vertical, transverse section, with parts shown in elevation, of a slate-cutter in a construction of which my improvements have been

embodied; and Fig. 2 is a view in front elevation of the same; Fig. 3 illustrates in perspective cutting apparatus having a plurality of cutting devices respectively embodying my improvements.

In the embodiment of my invention selected for illustration and description to enable ready and complete understanding of my improvements and referring first to Figs. 1 and 2, the part designated by the reference numeral 1 is a cutting member which may be of any suitable construction and material to effect the rapid and clean severance of such an article as the "inlaid slate" units to which I have already referred, composed of 60 pieces of slate cemented with asphalt to a backing of roofing paper in the preferred form of such units. As one convenient form of the aforesaid cutting member I have shown a blade of saw steel, provided with 65 teeth 2 along its forward edge, which may be formed in a convex curve in order to secure a desirable downward action of the edges of the teeth at every point of engagement with the article to be cut which in the 70 instance illustrated is an inlaid slate unit, bearing the reference numeral 3, this numeral designating the pieces of slate, while the reference numeral 4 designates the backing, and 5 the intervening layer of cement. 75 Preferably a suitable support will be provided for rigidly supporting one or more of the inlaid-slate units and this may take any suitable form, as for example, that designated by the reference numeral 6 which is 80 applied to the worktable proper, while 7 designates the upright walls of the box-like 85 structure upon which the worktable is 90 mounted.

I prefer to mount the pressure saw 1 pivotally upon the work-support as upon the bearing stud or arbor 8 at the rear of the worktable, which is shown in the instance illustrated as having a slot, the walls 9 of which serve as coöoperating shear members, with the saw blade, being preferably faced with angle strips of metal 10 for that purpose. Reinforcing strips 11 may also be provided as indicated in Fig. 2, upon the 95 vertical walls of the work-support.

The "inlaid slate" units are frequently made in rectangular form, either as "boards" approximately twice as long as their width, or as "squares," and when the 100 article to be trimmed has two of its mar-

gins parallel as in the above instances I prefer to provide the mill in which they are manufactured with apparatus for trimming at a single stroke two or more of these mar- 5 gins, and such apparatus may take any suitable form.

I have shown in Fig. 3, in perspective apparatus suitable for trimming a plurality of the edges of an inlaid slate unit or similar article whether in the form of a square or a longer rectangle, and it will be understood that I describe the rectangular form merely as a convenient illustration of the capabilities of this feature of my invention.

15 In Fig. 3 two pressure saws 24 and 25, of the type described above with reference to Fig. 1, are shown as mounted at 26 pivotally upon the support 27, and, for convenience and rigidity in operation these 20 saws may have cross connections at various points such as the stay-bar 28, and the cross handle 29, by which the operator may pull the saws down against any article placed upon the worktable 30 and extending over 25 the saw slots 31 which I prefer to provide with shoes or straight edges 32 to coöperate with the saws 24 and 25.

In order to relieve the operator of the necessity of lifting the saws after each cutting stroke, and to hold the saws normally in position for actuation, I may provide suitable counter-weights 33, serving as one convenient form of means to hold the saws in upright inoperative position. I prefer to 35 provide also suitable means to hold the articles to be trimmed upon the worktable firmly in adjusted position during the trimming operation, and any suitable form of such means may be provided. One convenient form of such means is shown at 34 40 in Fig. 3 as a flap or coverboard mounted pivotally near its rear edge on bearing studs or shafts 35 journaled in lugs 36, so that the board may be swung down on top of the 45 article to be trimmed or may be swung upward and away from said article.

In operation, the article having been placed upon the worktable 30, which is preferably deep enough transversely to receive 50 two squares in tandem relation to the operator who stands in front of the saws, the flap 34 will be brought down on top of the articles and will preferably be held there by suitable retaining means as for example, 55 the spring latch 37, while the operator grasps the handle bar 29 and actuates the

pressure saws as already described. The operator may then raise the saws and the flap 34, either in the order named or simultaneously, when the flap will aid the squares to 60 free themselves from the saws, and if desired suitable means, such as the latch 38 may be provided to hold the flap up out of the way of the operator, the latch engaging the bar 28 for this purpose, in the instance 65 illustrated.

Having described my invention thus fully and suitable means for carrying same into effect, it will be understood that I do not limit myself to the specific construction and 70 materials illustrated and described, nor in general otherwise than as set forth in the claims read in connection with this specification.

What I claim as new, and desire to secure 75 by Letters Patent is:—

1. Cutting apparatus; comprising a work table; and an extended saw blade having near one end a fulcrum mounted on said table, said blade presenting a serrated edge 80 of radius shorter than the length of the blade for acute sawing relation in every position of operative engagement progressively with said work as the latter lies stationary upon said work table. 85

2. Cutting apparatus; comprising a support for the article to be cut; and a plurality of crescent saws of radius shorter than their length respectively, and spaced apart to engage and saw said article to a 90 predetermined shape; said saws each having near one end a fulcrum mounted on said support; substantially as described.

3. Cutting apparatus; comprising a support for a flat slate or similar article to be 95 cut; two crescent shaped saws spaced widely apart and arranged in parallelism to engage said article and square the same; a pivoted clamping leaf to engage said article between said members and clamp said article in position on said support; and means to enable said leaf to be cleared from the work independently of said saws; substantially as described. 100

Signed at New York, in the county of New 105 York and State of New York, this 14th day of December, 1908.

JAMES H. MUNRO.
